UNITED STATES PATENT OFFICE.

FRANK KUHN AND FRANK E. SHAILOR, OF DETROIT, MICHIGAN, ASSIGNEES TO AMERICAN ELECTRICAL HEATER COMPANY, OF DETROIT, MICHIGAN, A CORPORATION OF MICHIGAN.

CONNECTOR FOR ELECTRICALLY-HEATED INSTRUMENTS.

1,170,168.

Specification of Letters Patent.

Patented Feb. 1, 1916.

Application filed July 9, 1914. Serial No. 849,938.

To all whom it may concern:

Be it known that we, FRANK KUHN and FRANK E. SHAILOR, citizens of the United States of America, residing at Detroit, in the county of Wayne and State of Michigan, have invented certain new and useful Improvements in Connectors for Electrically-Heated Instruments, of which the following is a specification, reference being had therein to the accompanying drawings.

The invention relates to connectors designed for use on electrically heated instruments such as sad irons and other movable tools.

15 The invention comprises the means employed for attaching said connector and for protecting the same mechanically and electrically as hereinafter set forth.

In the drawings: Figure 1 is a section 20 through a portion of an electrically heated iron to which the connector is applied; Fig. 2 is a horizontal section; Fig. 3 is a perspective view of one of the insulator blocks; Fig. 4 is a perspective view of one of the 25 sections of the housing; and Fig. 5 is a perspective view of a portion of the casing, with the complementary section of the housing connected thereto.

A is an electrically heated instrument 30 such as a sad iron; B is the heating unit therefor; C are terminals secured to the unit B and projecting upward therefrom; and D is an apertured casing through which the terminals C project.

35 The flexible conductor E is secured to the terminal C by clamping screws F or equivalent means for maintaining good electrical contact. The terminals and adjacent portion of the conductor are then inclosed in an 40 insulator block G which is provided with channels H for receiving the terminals and their clamping screws, and extensions of said channels I for receiving the adjacent portions of the flexible conductor. The 45 channels I are bent angularly to pass to one side of the block G and to produce the necessary frictional resistance for preventing the transmission of strain to the terminals.

50 J is a handle for the instrument detachably engaging the housing D.

K is a housing for the block G and which is formed in two sections K' and K² having a clamping engagement with each other.

The section K' is attached to a portion of the handle J and is provided with flanges K² which embrace opposite sides of the block G. The section K² has the flanges K⁴ for embracing the opposite sides of the block G and these flanges have a snap clamping engagement with the flanges K³ so that together said sections K' and K² form a complete housing for the block. The section K' is provided with a projecting portion L which is bent to embrace the flexible conductor and to secure a resilient helix M, which forms a guard for said conductor. Thus the handle will hold the section K' in position, while the latter will secure the section K² and the extension L so that mechanical stresses transmitted through the cord or flexible conductor will not be transmitted to the terminals but will be resisted by the housing K.

The construction is one which has the advantage of being easily assembled, permitting the detachment of the cord at any time for repair or for renewal while at all times, when the instrument is in use, a clamping engagement between the flexible conductor and terminal is maintained, thereby preventing arcing.

What we claim as our invention is:—

1. In an electrically heated instrument, the combination with a heating unit having a terminal projecting therefrom, of a casing for inclosing said unit apertured for the passage of said terminal, a handle for said casing, a flexible conductor having a clamping engagement with said terminal, an insulator block for embracing said terminal and adjacent portion of said flexible conductor, a metallic housing having a section thereof secured to said handle and embracing said insulator block, and a complementary portion of said housing having a snap engagement with said attached section.

2. In an electrically heated instrument, the combination with an electrical heating unit, of a terminal projecting therefrom, a casing for inclosing said unit apertured for the passage of said terminal, a handle for said casing, a flexible conductor having a clamping engagement with said terminal, an insulator block channelled for the reception of said terminal and having an extension angular channel for the passage of said flexible conductor, a metallic housing sec-

tion secured to said handle and embracing said insulator block, a guard for said flexible conductor mounted upon said housing section, and a complementary section for said metallic housing having a snap engagement with said fixed section and completely enclosing said insulator block.

In testimony whereof we affix our signatures in presence of two witnesses.

FRANK KUHN.

FRANK E. SHAILOR.
